UNITED STATES PATENT OFFICE.

HARRY DAVID RINDSBERG, OF CINCINNATI, OHIO, ASSIGNOR TO HARRY J. HATER, OF CINCINNATI, OHIO.

MOLD.

Application filed April 2, 1926. Serial No. 99,407.

My invention relates to improvements in permanent metal molds of the kind used in making castings from metals and metallic alloys such as aluminum and its alloys which have comparatively low fusing points, although not necessarily restricted to this type of mold. More particularly the invention relates to molds of this type for producing hollow or cup shaped cylindrical castings such as skirted pistons for internal combustion engines, although capable of other uses.

Specifically the present invention relates to certain improvements in the molding device shown and described in the patents to Owen et al., No. 1,538,584 of May 19, 1925, and Schnobrich No. 1,525,893 of February 10, 1925.

The invention relating to the core drawing apparatus and core supporting rack is claimed in divisional application No. 219,520, filed September 14, 1927.

An important object of my invention is to provide a mold of the above mentioned character which is capable of operation by a single workman.

Another object of my invention is the provision, in a device of this character, of means whereby the mold sections may be cleaned and repaired without being separated from the rest of the mold.

A further object of my invention is to provide a device of this character which is removably mounted on a support, the support being capable of use with different molds.

Still another object of my invention is to provide improved means for removing the center core section.

A still further object of my invention is to provide an adjustable core supporting rack to accommodate different workmen.

Other objects and advantages of my invention will be apparent during the course of the following description.

In the accompanying drawings, wherein like characters of reference denote like or corresponding parts throughout the same—

Figure 1 is a side elevation of my improved molding machine,

Figure 2 is a top plan view thereof,

Figure 3 is a central longitudinal sectional view thereof,

Figure 4 is a side elevation of the same,

showing the separated position of the mold sections,

Figure 5 is an end elevation of the molding machine,

Figure 6 is a central transverse sectional view thereof,

Figure 7 is a detail perspective view of one of the mold sections illustrating the manner in which it may be raised,

Figure 8 is a detail sectional view of the connection between the core members and rack bars,

Figure 9 is a detail view of the core balance supporting swivel, parts being in section, and

Figure 10 is a detail perspective view of the mold support, and core rack portions of the core rack being broken away.

I have selected for purposes of illustration, a "one man mold" of the type shown in the above mentioned patents, although the present invention is by no means limited to a mold of this special type.

In the drawings, wherein for the purpose of illustration is shown a preferred embodiment of my invention, the numeral 1 designates a suitable base plate on which a pair of separable mold sections 2 and 3 are mounted as is usual. The meeting faces of these sections are so shaped as to form a mold cavity 4, which in the case of a piston mold, is of course circular in plan.

A gate or inlet leading to the mold cavity 4, is also formed in the meeting faces of the two mold sections as indicated at 5 in Figure 6, and so far as the present invention is concerned, this gate may be of any desired construction.

The drawings show seven cooperating core members, fitting within the upper part of the mold cavity, although the invention may be used where other numbers of core members are utilized as for instance, three or five. These core members are clearly shown in Figure 2 and comprise a central member 7 flanked by a pair of associated members 10, 11, 12, and 13 fitting in pairs at each side of the central group. The construction and manipulation of these core members is too well known in the art to require detailed description here.

The three middle members 6, 7, and 8 are provided with upstanding rods or han-

dles 9 by which they may be manipulated, and an arm having a handle at its end is also rigidly secured to each of the four core members 10, 11, 12, and 13, such arms extending in the same general direction and being substantially horizontal.

The arms are designated by the characters 14, 15, 18, and 19, the arms 14 and 15 being bent around through substantially 180 degrees and the four handles carried by the arms are designated 16, 17, 20, and 21 respectively.

In order to properly position the core members 10 and 11, and 12 and 13, I preferably provide pins 22 and 23 set into the mold sections 2 and 3 respectively, adjacent the meeting edges of the core members, as clearly shown in Figure 3.

Set into opposite sides of the mold sections 2 and 3 are two pairs of pins or studs 24, these studs preferably having reduced threaded ends 24^a which are screwed into suitable openings in the mold sections. The studs forming each pair are parallel and spaced slightly apart, and their outer ends are reduced and threaded, as shown at 25. A plate or bracket 26, having a slot 27 therein, fits over the ends 25 of each pair of studs 24 and is secured in position thereon by means of nuts 25^a. By virtue of the slot 27, the plates 26 may be adjusted slightly if required.

The lower ends of the plates or brackets 26 are forked, as shown at 28 and these forked ends are so shaped as to snugly fit over racks 29 circular in cross section and provided with teeth on their upper sides. To the inner end of each rack is secured a core member 30, such member forming, in effect, a continuation of the rack body and being in alignment therewith. These core members 30 slide freely through the side walls of the mold sections 2 and 3, and the outer ends of the racks 29 are slidably mounted in brackets 32, adjustably secured to the ends of the base plate 1. Each of these brackets is provided with a pair of slots 34 through which work bolts 33 as shown in Figure 5.

Interposed between the end of each rack 29 and the adjacent wall of the mold section and surrounding and rigidly secured to the core member 30 is a collar 31. This collar is of such size that it cannot pass through the forked end of the bracket 26, but will engage with the prongs 28 thereof, for a purpose hereinafter described.

One of the racks 29 is in engagement with a pinion 37, secured to a shaft 38, journaled in extensions 32^a of the bracket 32, and extending a considerable distance beyond said bracket as indicated at 38^a in Figure 2, this extended portion preferably being enlarged. At the extreme end, this enlarged portion 38^a of the shaft 38 carries an

operating lever 39 having an arm 40 pivotally connected at 41 with a link 42. The other end of this link is itself pivotally connected at 43 with a crank arm 44, secured to a shaft 45, journaled in extensions 32^a 70 of the other bracket 32 at the other side of the mold, and having rigidly mounted thereon a pinion 46 which engages with the other rack 39.

The bottom of the mold cavity is formed by means of a pair of plates 34 and 35 secured to the lower ends of the mold sections 2 and 3 respectively, as by screws 36. These plates cooperate with the mold sections proper to completely enclose the mold cavity, 80 entirely independent of the base of the machine. Spaced runways or rails 47 are provided upon which the mold sections are slidably mounted. By reference to Figure 6 it will be seen that these rails are disposed 85 one at each side of the frame and are so positioned relative to the plates 34 and 35 that these plates lie between, but out of contact with the supporting rails. Each rail 47 is provided along its outer edge with an 90 upstanding guide flange 48, the mold sections fitting snugly between such guide flanges, as shown in Figure 6.

From the foregoing it will be obvious that when the lever 39 is swung upwardly from the position shown in Figure 3, the two pinions 37 and 46 will be simultaneously rotated, and will cause the racks 29 to travel simultaneously in opposite directions. The first part of this movement results in withdrawing the core members 30 from the cavity of the mold. After this initial movement, a further movement in the same direction causes the collars 31 to engage the lower forked ends of the brackets 32, and 100 thus, as the movement of the racks continues, these brackets, together with the mold sections 2 and 3 to which they are attached, are simultaneously moved away from each other or in opposite directions, such sections sliding upon the runways 47 as they are moved.

In order to lock the mold sections tightly together during the casting operation, as has already been proposed, a pair of latches or hooks 49, mounted one at each side of the 115 mold, are provided and are adapted to engage pins 50, set into one of the mold sections, and are so formed that the point or beak of the hook underlies the pin, when in locked position. In order therefore to disengage the hooks from the pins it is necessary to first move them longitudinally so that the beak will clear the pins when the hooks are swung upwardly on their pivots. In order to accomplish this, each hook is 120 journaled upon an eccentric 51, these eccentrics being rigidly secured to a shaft 52 journaled in the mold section 3. The ends of the shaft 52 are extended beyond the eccentrics 125 and carry transversely disposed radially pro-

jecting pins 56. These pins are adapted to engage pins 55 carried by the hooks 49, so as to elevate the hooks into release position as the shaft 52 is rotated. In order to rotate this shaft, I secure to one end thereof a crank arm 53 provided at its end with a handle 54.

In order to facilitate the work of the single operator of this machine of the "one man type", and to avoid possible damage to the core members, I provide a special holder to receive these core members when they are removed from the mold cavity. This holder comprises a pair of upstanding arms or side members 57 secured to a mold support hereinafter described. To the upper ends of the side members 57, a pair of inclined pans or trays 58 and 59 are adjustably secured by means of integral brackets or lugs 58^a and 59^a held in place by bolts 59^b which fit in openings 59^c, there being a sufficient number of openings to allow of a large range of adjustment. Each of these pans or trays may conveniently be made of cast iron or the like but are provided with a lining 60 of sheet brass or other relatively soft metal so as to prevent damage to the core members when the same are placed therein.

Segment plates 61 are interposed between the mold support and the arms 57, the arms 57 being adjustably secured thereto by means of pivot bolts 62 arranged at the lower ends of the segment plates and adjusting bolts 63 extending through arcuate slots 64 in the plates 61. It will be seen that not only may the trays be adjusted for different workmen, but the supporting arms 57 are capable of a large range of adjustment by moving the adjusting bolts 63 in the slots 64. In this way different sizes of workmen may be readily accommodated.

Arranged at the upper end of one of the arms 57 is a swivel connection comprising a body portion 65 bolted to the arm 57 and having a vertical bore in its upper end for the reception of a swivel pin 66 carried by a forked swivel 67. The crotch of the fork is substantially inverted V-shape in cross-section as shown at 68 in Figure 9.

A balance arm 69 is pivotally connected between the arms of the fork at 70 and rests upon the apex of the V at 68. It will be seen that the balance arm is capable of swiveling about an angle of 360 degrees and is also capable of pivoting about the connection 70 by reason of the V-shaped portion 68.

One end of the balance is provided with a weight 71 adjustably clamped to the arm by means of the bolt 72. The other end of the balance is provided with a chain 73 or similar device provided at its lower end with a suitable connection 74 for detachably engaging the arm 9 of the center core section 7. It will be seen that when the core sections are to be removed, the balance arm can be drawn

down and the chain connection 74 attached to the handle 9 of the core section 7 and that the weight 71 will withdraw the core section as shown in Figure 4. The balance can then be swung out of the way and the remaining 70 core sections can be readily removed and placed in the trays. It is to be understood, however, that the balance may be used on molds having any number of core sections, and that although seven such sections are 75 shown, such showing is merely for the purpose of illustration.

In order to adapt the mold to ready cleaning and repairing, I provide a pivotal connection between the racks 29 and cores 30. 80 This connection comprises a ball joint 75 carried by the core 30 and keyed thereto at 76. This ball rests in a socket 77 in the rack 29 and is pivotally held therein by means of a transverse pin 78 which extends through 85 an opening 79 in the ball, the opening 79 being of substantially larger diameter than the pin to allow the ball to rest on the bottom of the socket and thus take the strain from the pin, as clearly illustrated in Fig- 90 ure 8.

Openings 80 are provided on each side of the mold sections 2 and 3 and are adapted to receive the ends of removable handles 81 by which the mold sections may be raised 95 about the pivot pin 78 to be repaired or cleaned as shown in detail in Figure 7 and in dotted lines in Figure 4. By this arrangement it is not necessary to remove the sections 2 and 3 from the mold and consequently the sections do not become cold.

In order to readily use molds of various sizes I provide a detachable support for the mold. This support comprises legs or other supporting means 82 bolted or otherwise 105 rigidly secured to transverse angle bars 83. Longitudinal angle bars 84 are rigidly secured to the transverse bars 83 at their ends and cooperate therewith to form a rectangular frame. The upstanding sides 85 of the 110 longitudinal angle bars 84 are provided with bolts 86 which extend therethrough.

In operation, the mold base 1 is placed between the bars 84 and the bolts tightened until they firmly bear against the base 1 as 115 shown in Figure 6. It will be seen that the mold will be held securely in place, but may be readily removed and replaced by another mold. This construction obviates the necessity for a supporting base, core rack and 120 balance arm for every mold, and its attendant inconveniences.

While I have shown and described the preferred embodiment of my invention, it is to be understood that various changes in the 125 shape, size, and arrangement of parts may be resorted to without departing from the spirit of my invention or the scope of the subjoined claims.

Having described my invention, what I 130

claim and desire to protect by Letters Patent is:

1. In a device of the character described, a mold comprising a pair of separable sections, a base plate on which said sections are supported for relative sliding movement, means to slide said sections in opposite directions, and means allowing said sections to be swung away from the support.
2. In a device of the character described, a mold support, a mold thereon comprising a pair of separable sections, said sections being capable of movement relative to the mold support in the same plane and in different planes.
3. In a device of the character described, a mold comprising a pair of separable sections, one of said sections being capable of movement in a horizontal plane and in an arcuate path which intersects the horizontal plane of movement at substantially a right angle.
4. In a device of the character described, a mold comprising a pair of separable sections, one of said sections being capable of movement in a plane and being also capable of movement in an arc.
5. In a device of the character described, a mold comprising a pair of separable sections, a base plate on which said sections are supported for relative sliding movement, a bar pivotally connected to one of the mold sections, and means to move the bar to separate the mold sections, one of the sections being capable of being moved about the pivot connection with the bar.
6. In a device of the character described, a mold comprising a pair of separable sections, a base plate on which said sections are supported for relative sliding movement, an operating bar having a socket, an extension on one of the mold sections having a ball adapted to fit within the socket, and means to move the operating bar to separate the mold sections.
7. In a device of the character described, a mold comprising a pair of separable sections, a base plate on which said sections are supported for relative sliding movement, an operating bar having a socket, an extension on one of the mold sections having a ball adapted to fit in the socket in the operating bar, a pin securing the ball in the socket, means whereby the strain of the mold is placed on the socket to preserve the pin, and means to move the operating bar to separate the mold sections.
8. A device of the character described, comprising a pair of mold sections, supporting means on which said sections are slidably mounted, racks operatively associated with said sections, pinions meshing with the racks, means to rotate the pinions to separate the sections, and pivotal connections be-

tween the sections and the racks to allow the sections to be swung away from the supporting means.

9. A device of the character described comprising a pair of mold sections, supporting means on which said sections are slidably mounted, a rack operatively associated with one of said sections, said rack being provided with a socket, an extension carried by the section associated with said rack, said extension having a ball adapted to fit in the socket of the rack, a transverse pin extending across the socket and fitting in a transverse opening in the ball, the opening in the ball being of substantially greater diameter than the pin, whereby the ball will always rest on the walls of the socket, a pinion meshing with the rack, and means to rotate the pinion to separate the sections.

10. A device of the character described, comprising a mold having a pair of separable sections each containing complementary parts of the mold cavity, a base plate on which said sections are supported for relative sliding movement, said sections having openings extending through the walls thereof in alignment with each other, a pair of core members permanently carried by said mold sections and slidably mounted in said openings, said core members when in operative position projecting toward each other into the mold cavity, and having their outer ends extending beyond the mold sections, balls on the ends of the core members, racks having sockets to receive said balls, and means to move the racks to withdraw the core members from the mold cavity and separate the mold sections.

11. A device of the character described, comprising a mold having a pair of separable sections, each containing complementary parts of the mold cavity, a base plate on which said sections are supported for relative sliding movement, a rack adjustably secured to the mold, a balance arm pivotally secured to the rack, core members arranged in the cavity of the mold, means connecting the balance arm with one of the core members to withdraw said core member, said mold sections having openings extending through the walls thereof in alignment with each other, a pair of aligned core members permanently carried by said mold sections and slidably mounted in said openings, said core members, when in operative position projecting toward each other into the mold cavity and having their outer ends extending beyond the mold sections, rack bars pivotally connected to the outer ends of the aligned core members, and means to move the rack bars to withdraw the aligned core members and separate the mold sections.

In testimony whereof I affix my signature.
HARRY DAVID RINDSBERG.
